UNITED STATES PATENT OFFICE

92,770

DESIGN FOR A SLICING MACHINE

Ernest Albert Reussenzech, Dayton, Ohio, assignor to International Business Machines Corporation, New York, N. Y., a corporation of New York

Application May 19, 1934, Serial No. 51,841

Term of patent 14 years

To all whom it may concern:

Be it known that I, ERNEST ALBERT REUSSENZEHN, a citizen of the United States, residing at Dayton, in the county of Montgomery and State of Ohio, have invented a new, original, and ornamental Design for Slicing Machines, of which the following is a specification, reference being had to the accompanying drawings, forming a part thereof.

Fig. 1 is an elevational view of one side of the slicing machine, showing my new design.

Fig. 2 is an elevational view of the other side thereof.

Fig. 3 is a plan view thereof, and

Fig. 4 is a view thereof from the operator's end.

I claim:

The ornamental design for a slicing machine as shown.

In testimony whereof I hereto affix my signature.

ERNEST ALBERT REUSSENZEHN.
